(57) **CLAIM**

The ornamental design for a dispenser case, as shown and described.

DESCRIPTION

FIG. 1 is a perspective view of a dispenser case showing the new design;

FIG. 2 is a front view thereof;

FIG. 3 is a rear view thereof;

FIG. 4 is a left side view thereof;

FIG. 5 is a top view thereof;

FIG. 6 is a front perspective view thereof showing the dispenser case in a folded position;

FIG. 7 is a rear perspective view thereof;

FIG. 8 is a left side view thereof;

FIG. 9 is a right side view thereof;

FIG. 10 is a top view thereof;

FIG. 11 is a perspective view thereof showing the dispenser case with notes; and,

FIG. 12 is another perspective view thereof showing the dispenser case with notes.

The portions of the dispenser case in FIGS. 1-3, 6, and 8-10 shown in broken lines are included to show features that form no part of the claimed design.
